(57) **CLAIM**

The ornamental design for a punching and binding machine, as shown and described.

DESCRIPTION

FIG. 1 is a perspective view of the punching and binding machine shown in closed position;

FIG. 2 is a perspective view of the punching and binding machine shown in open position;

FIG. 3 is a first side view of the punching and binding machine of FIG. 2;

FIG. 4 is a second side view of the punching and binding machine of FIG. 2;

FIG. 5 is a back view of the punching and binding machine of FIG. 2;

FIG. 6 is a front view of the punching and binding machine of FIG. 2;

FIG. 7 is a bottom view of the punching and binding machine of FIG. 2; and,

FIG. 8 is a top plan view of the punching and binding machine of FIG. 2.
